UNITED STATES PATENT OFFICE.

ERNST CASPARY, OF ALTENA, GERMANY.

COLLAR-SUPPORTER.

1,021,916.

Specification of Letters Patent.

Patented Apr. 2, 1912.

Application filed November 15, 1910. Serial No. 592,555.

To all whom it may concern:

Be it known that I, ERNST CASPARY, a citizen of the German Empire, residing at Altena, in the Province of Westphalia and 5 Kingdom of Prussia, Germany, have invented certain new and useful Improvements in Collar-Supporters; and I do hereby declare the following to be a full, clear, and exact description of the invention, such as 10 will enable others skilled in the art to which it appertains to make and use the same.

This invention relates to a new or improved manufacture of stiffeners for ladies' collars and the like. Many different forms 15 of such stiffeners have been proposed and it is usual to employ strips of celluloid, metal or similar material sewn or secured to the dress. It has also been proposed to employ one or more strips of such material 20 covered with woven or braided material and bent around at the end and bound or secured in the middle. It has further been proposed to employ stiffening strips made of the material known as "featherbone" and composed 25 of a main central cord and two outer cords of the fiber of quills united by threads applied by winding and stitching. These various stiffeners present drawbacks. Some 30 are liable to buckle in the middle under pressure in use, others will not stand washing; whalebone, for example splits when wet. Moreover in the covered types the stiffening strip is often liable to break and penetrate the covering so as to cause great 35 inconvenience to the wearer.

Now by the present invention I am enabled to obviate these disadvantages and to provide a stiffener which will withstand washing while possessing yielding and supporting qualities which insure perfect comfort in wear, and without liability for the stiffening material to break or pierce the covering material. For this purpose the invention is characterized by the employment 40 of a body or core of horsehair, preferably in the form of loose lengths. This core is covered with a braided, woven, wound, or other layer of cotton, silk or other material.

50 The stiffener may be made in various shapes and forms. In the preferred form it comprises two ends each formed of a bundle of lengths of horsehair bent into a loop, and an intermediate stiffening portion. 55 If desired the horsehair may be in continuous lengths forming both the end loops and

extending the full length of the device, but I prefer to make the loops of separate bundles, the free ends of which may extend about half the length of the intermediate 60 stiffening portion. The horsehair cores are covered by a braided layer which preferably incloses the eyes of the loops. A separate tubular braided layer may with advantage be provided for each horsehair core when 65 two are employed. The intermediate portion is stiffened by the insertion of a metal wire inside the tubular braided intermediate portion or portions, and by folding and flattening upon the latter a strip of flexible 70 metal and covering the same with cotton, silk or other suitable material, this strip when thus folded forming a flexible metallic casing for the middle part of the stiffener and overlapping the inner ends of the textile covering above mentioned. If desired other means of stiffening the intermediate portion may be employed.

75 The accompanying drawings show by way of example a stiffener made according to the 80 invention.

Figure 1 is a part sectional elevation and Fig. 2 is an elevation at right angles in Fig. 1.

This is made at the ends with cores *a* of 85 loose lengths of horsehair bent into loops and extending to about midway of the intermediate portion. *b* is a woven or braided covering of cotton or the like somewhat enlarged at the ends to inclose and cover the 90 eyes of the loops *a* and likewise extending to about midway of the intermediate portion.

c is a wire of suitable length inserted in the tubular lengths of woven or braided material and *d* is a strip of pliable metal folded and flattened around the sides of the stiffener to give greater strength and *e* is a winding of cotton upon the strip *d*.

95 If desired the stiffener may be made with 100 only one end loop instead of two.

Having now described my invention I declare that what I desire to secure by Letters Patent is:

105 1. A collar support consisting of a bundle of looped horsehairs, a covering for said loop, a metallic casing covering a portion of said bundle and a wire within said bundle.

110 2. A collar support consisting of two loops of horsehair with their ends presented toward each other, a wire between and ex-

tending into the end of each loop, and a metal piece inclosing said wire and the ends of said loops.

3. A collar support comprising two covered loops of hair with their ends presented toward each other, a wire entering the end of each loop and a covering holding said loops and said wire together in position.

4. A stiffener for ladies' collars and like articles consisting of a bundle of horsehairs, formed into a pair of terminal loops and a

middle part, a wire extending at its ends into said loops, coverings for said loops and a casing for said middle part overlapping the inner ends of said loop-coverings.

In testimony whereof, I have signed my name to this specification in the presence of two subscribing witnesses.

ERNST CASPARY. [L. s.]
